FUSE.

1,150,569.

Specification of Letters Patent. Patented Aug. 17, 1915

Application filed June 7, 1913. Serial No. 772,385.

To all whom it may concern:

Be it known that I, WILLIAM C. BANKS, a citizen of the United States, residing in the borough of the Bronx, city and State of New York, have invented certain new and useful Improvements in Fuses, of which the following is a specification.

This invention relates to fuses for use in protecting electric circuits from the flow of excessive current.

More particularly, the invention relates to electric fuses of the type comprising the combination of a fusible metallic strip, a tube of insulating material inclosing the same and means for securing the ends of the fusible strip rigidly to the ends of the inclosing tube.

In fuses of this type as heretofore constructed it has been proposed to employ gripping members at each end of the tube lying on opposite sides of the fusible strip, so arranged that they may be moved lengthwise of the fuse and when so moved will be caused to grip the ends of the fusible strip by a wedge action. This invention relates to fuses of this character and involves the provision of means whereby one or more of the gripping members will be held against rotational movement while it is being moved lengthwise of the fuse to cause it to grip the strip. If no means were provided for guarding against such rotational movement of the gripping members, such rotation might take place and might lead to distortion or breakage of the fusible strip and thus cause the fuse to operate improperly or not at all. For the purpose of preventing such rotational movement of the gripping members, I provide projections upon one or more of the gripping members adapted to be received in recesses formed in the inclosing tube of the fuse, and serving to hold the gripping member from turning about the axis of the tube as the member is moved in the direction of the length of the fuse.

A further feature of the invention involves the provision of means for locating one or more of the gripping members with reference to the fusible strip. In accordance with this feature of the invention the strip proper is secured at its ends to terminal members and one or more of the gripping members are provided with projections adapted to enter recesses in the adjacent

terminal members. By reason of this provision the parts of the fuse may be assembled more rapidly than has been the case heretofore without danger of the central portion of the fusible strip being displaced from the center of the length of the fuse.

The preferred embodiment of the invention is illustrated in the accompanying drawings in which—

Figure 1 is a central section of a fuse, Fig. 2 is a central section at right angles to the section of Fig. 1 with certain of the parts detached, Fig. 3 is an elevation of one end of the fuse with the cap detached from the tube and Fig. 4 is a transverse section on line 4—4 of Fig. 3.

Referring to these drawings, a fusible strip is shown at 5, this passing lengthwise through an inclosing tube 6 of insulating material. The ends of strip 5 may be secured directly to the ends of the inclosing tube, if desired, but I prefer to secure the ends of the strip 5 to terminal members of thicker and stronger metal and to secure these terminal members to the ends of the inclosing tube. The terminal members are shown at 7 and they are preferably short bars of copper. The ends of the fusible strip 5 are secured to these terminals 7 by suitable nuts and bolts 8.

For the purpose of securing each terminal member 7 to the adjacent end of the tube 6, two gripping members 9 are provided at each end of tube 6, the two members 9 of each pair lying on opposite sides of the terminal member 7 at that end of the fuse. These gripping members 9 are semicircular in shape as shown in Fig. 4 and they are tapered or wedge-shaped upon their curved surfaces. The tapered formation of these gripping members is shown in Fig. 2.

Each end of the tube 6 is threaded and is adapted to receive an interiorly threaded cap 10. This cap is placed upon the end of the tube 6 and screwed up thereon so that the inwardly turned flange 11 at the end of the cap engages the gripping members 9 and as the cap is screwed up further, it will move the gripping members 9 in the direction of the length of the fuse. As the gripping members 9 are so moved, they will be caused to move toward each other by the coaction of their wedge-shaped or tapered surfaces with the interior wall of the tube 6 at the

end of the tube, and these gripping members will therefore grip the terminals 7 between them to hold those terminals and the strip 5 rigidly with respect to the tube 6.

It will be observed that if the pairs of gripping members 9 were allowed to turn more or less about the axis of tube 6 with the coacting cap 10 as the latter is turned, the two terminals 7 would be turned in opposite directions with the result that the strip 5 would be twisted. This might result in breaking the strip 5 in which event the fuse would not be usable, but even if the strip 5 were not broken such twisting would be very objectionable. It might materially alter the volume of current which would cause blowing of the fuse. In order to prevent such twisting movement of the fuse, I provide means for holding the gripping members 9 against rotational movement with respect to the tube 6, particularly rotational movement with the adjacent cap 10. For this purpose I provide one gripping member 9 of each pair with a projection 12 which projection is adapted to enter a recess in the tube 6, such, for instance, as the recess shown in Fig. 3, cut in the end of the tube. Projections 12 with their corresponding recesses may be provided on each gripping member 9, but I find it sufficient to provide one on one gripping member of each pair. It will be seen that when the gripping members are assembled as shown in Fig. 2, with the projections 12 in the recesses provided therefor, the screwing up of the cap 10 upon the end of tube 6 will not cause turning movement of the members 9; as the cap is forcing the members 9 to their final gripping positions, the flange 11 of the cap will slide upon the surface of members 9 without turning those members.

As shown in Fig. 2, one of the projections 12 consists of a pin which passes through one of the gripping members 9 and projects on the straight side thereof as well as on the semicircular side. The end 13 of this pin projecting from the straight side is adapted to be received in an opening provided therefor in the coacting terminal 7. When assembling the parts, the strip 5 with its terminals is positioned within tube 6 and the gripping member 9 provided with the projection 13 is then positioned with the projection 13 in the opening in terminal 7 and the projection 12 in the recess in tube 6. The coacting terminal 7 may then be positioned and the cap 10 applied at this end of the fuse. This procedure insures proper positioning of the strip 5 with reference to the length of the fuse; in other words, the use of the projection 13 coacting with a properly positioned recess in the terminal 7 insures that the center of strip 5 will be at the center of tube 6.

Having described my invention, what I claim as new therein and desire to secure by Letters Patent of the United States is:

1. The combination of a fuse, a tube of insulating material inclosing the same, a pair of gripping members lying on opposite sides of the fuse at each end of the tube, and projecting beyond the end of the same and having inclined outer surfaces whose greatest diameter exceeds the interior diameter of the tube, a cap mounted upon each end of the tube and so formed as to contact the outer ends of said gripping members at that end of the tube, when moved inwardly, axially of the tube, to move said members inwardly axially of the tube, said members and parts coacting therewith being so formed that such axial movement of said cap results, by a wedging action, in movement of said members toward each other into gripping relation to the fuse and means for preventing turning of the gripping members relatively to the tube, substantially as set forth.

2. The combination of a fuse, a tube of insulating material inclosing the same, a pair of gripping members lying on opposite sides of the fuse at each end of the tube and having inclined outer surfaces whose greatest diameter exceeds the interior diameter of the tube, a cap threaded upon each end of the tube and adapted when turned upon the tube to engage the adjacent gripping members and move them in the direction of the length of the fuse and means for preventing turning of the gripping members relatively to the tube, substantially as set forth.

3. The combination of a fuse, a tube of insulating material inclosing the same, a pair of gripping members lying on opposite sides of the fuse at each end of the tube and having inclined outer surfaces whose greatest diameter exceeds the interior diameter of the tube, a cap threaded upon each end of the tube and adapted when turned upon the tube to engage the adjacent gripping members and move them in the direction of the length of the fuse and a stud on one of the gripping members entering a notch in the end of the tube, substantially as set forth.

4. The combination of a fuse, a tube of insulating material inclosing the same, a pair of gripping members lying on opposite sides of the fuse at each end of the tube, a cap threaded upon each end of the tube and adapted when turned upon the tube to move the adjacent gripping members toward each other in gripping relation to the fuse and means adapted to lock together a gripping member and the fuse against relative movement in the direction of the length of the fuse, and thus insuring the positioning of a gripping-member upon the

fuse at a desired point in the length of the fuse, substantially as set forth.

5. The combination of a fuse, a tube of insulating material inclosing the same, a pair of gripping members lying on opposite sides of the fuse at each end of the tube and having inclined outer surfaces whose greatest diameter exceeds the interior diameter of the tube, a stud on one of the gripping members entering and closely fitting with

upon each end of the tube and adapted when turned upon the tube to engage said members and move them in the direction of the length of the fuse, substantially as set forth.

This specification signed and witnessed this 3 day of June, 1913.

WILLIAM C. BANKS.
